UNITED STATES PATENT OFFICE

JAMES D. FONVILLE, JR., OF ABILENE, TEXAS

PUMP

Application filed March 28, 1931. Serial No. 526,077.

The present invention relates to pumps and more particularly to pumps adapted for use in emptying shallow pools or the like.

An object of this invention is to provide a pump which is so constructed as to readily lift or withdraw water and other material out of pools or the like, and embodying means whereby the working parts of the pump will not be clogged up through accumulation of solid matter.

Another object of this invention is to provide, in a pump of this kind, means for cutting solid particles prior to entrance of the articles into the pump mechanism.

A further object of this invention is to provide a readily portable pump of this kind in which all check valve members found in numerous pumps have been eliminated.

The above and various other objects and advantages of this invention will in part be described in and in part be understood from the following detailed description of the present preferred embodiment, the same being illustrated in the accompanying drawings, wherein:—

Figure 1 is a detail front elevation of a pump constructed according to the preferred embodiment of this invention;

Figure 2 is a vertical sectional view taken on the line 2—2 of Figure 1;

Figure 3 is a sectional view taken on the line 3—3 of Figure 2;

Figure 4 is a sectional view taken on the line 4—4 of Figure 2;

Figure 5 is a sectional view taken on the line 5—5 of Figure 2, and

Figure 6 is a detail plan view of one of the lifting elements used in the pump.

Referring to the drawings, wherein like numerals of reference designate corresponding parts throughout the several views, the numeral 10 designates generally a pump casing or housing comprising a pair of elongated tubular members 11 and 11' which have their abutting wall portions cut away so as to provide a substantially unitary housing structure of tubular construction. The housing or casing 10 is provided adjacent the upper end thereof with an outlet spout 12, and the lower end 13 of the housing is preferably

open, as at 13, so as to permit the liquids to pass upwardly through the housing 10.

Disposed longitudinally through the tubular section 11 is a pump shaft 14 which at the lower end thereof is rotatably mounted in a transversely disposed bearing 15 which is mounted in the lower end of the housing 10. The upper end of the shaft 14 extends through a cap or head 15, and a pulley 16 is secured to the upper end of the shaft 14, the pulley being adapted to receive a belt or be otherwise connected to a power member for rotation thereof. The cap 15 comprises a top plate 17 having downwardly extending flanges 18 engaging about the outer surface of the housing members 11 and 11', and a lug 19 is secured to each side of the housing 10 adjacent the upper end thereof for threadably receiving a bolt member 20 which extends through a securing bar 21.

This securing bar 21 is adapted to removably secure the head or cap 15 on the upper end of the housing 10. A gasket 22 is interposed between the inner surface of the cap 15 and the upper end of the housing 10 so as to effectively seal the cap within the housing. A second shaft 23 is disposed within the other tubular member 11' and is rotatably mounted at the lower end in the transversely disposed bearing 15' carried by the lower end of the housing 10 and the upper end of the shaft 23 extends through the head or cap 15. A gear 24 is mounted on the upper end of the shaft 23 and meshes with a drive gear 25 mounted on the drive shaft 14. In this manner, the shaft 23 will rotate reversely from the shaft 14.

A plurality of water lifting members or propellers generally designated as 26 are secured to the drive shaft 14 at spaced intervals therealong, these water lifting members or propellers 26 comprising a hub section 27 which engages about the periphery of the shaft 14 and is secured thereto by means of a securing pin 28 or the like. A plurality of spirally disposed blades 29 are secured to the hub 27 and the outer edges of these blades 29 extend closely adjacent the inner surface of the tubular member 11. The lower edge of each blade 29 is preferably disposed in a

substantially horizontal plane and is provided with a keen edge 30 so that any solid matter or the like being lifted upwardly through the tubular member 11 will be cut upon contact with the keen edge 30.

Disposed below the lowermost lifting member 26, there is mounted an article cutter generally designated as 31 which comprises a hub section 32 and a pair of opposed cutter blades 33 which are provided with keen edge portions 34, these blades 31 having a slight pitch so as to cooperate with the propeller blades 29 in raising water or the like in the tube 11. The shaft 23 is also provided with a plurality of lifting members 26 having blades 29 secured to the hub sections 27. These blades 29 are so arranged with respect to the blades 29 that the blades will overlap a slight distance, the lifting members 26 being mounted on the shaft 23 in such position that the blades 29 are slightly in advance of the blades 29. In this manner, the synchronization of the two blades is obtained so that any heavy articles or the like which are drawn upwardly through the tube sections 11 and 11' will not adhere to the blades 29 and 29' inasmuch as one blade will coat to remove the material from the blade on the other lifting member. In like manner, a second cutter member 31' is mounted on the shaft 23, the blades 33' of which are mounted at substantially right angles to the blades 33 of the cutter member 31. These blades also cooperate with the blades 33, in not only cutting the solid particles drawn through the housing 10, but also in removing the material adhering to the opposing blades. As shown in Figure 2, the shafts 14 and 23 are provided with roller bearings 35 and a packing gland member 36 is adapted to seal the roller bearings 35 in the bearing support 15.

In the operation of this device, the pulley 16 may be connected to a suitable power member by means of a belt or the like, so as to rotate the drive shaft 14, at a relatively rapid rate, which rotation will also rotate the driven shaft 23 reversely but at the same rate as the drive shaft 14. The lower end 50 of the housing 10 may be projected into the desired liquid and upon rotation of the lifting members 26 and 26' with the shafts 14 and 23, respectively, the liquids together with any relatively solid matter will be forced upwardly through the tubular sections 11 and 11' and forced outwardly through the spout 12. While the spout 12 is mounted on the tubular section 11', I do not wish to be limited to this construction as, if desired, the spout 12 may be connected to either of the tubular sections or disposed intermediate thereof and in communication with each housing.

It is, of course, understood that various changes and modifications may be made in

the details of construction and design of the above specifically described embodiment of this invention without departing from the spirit thereof, such changes and modifications being restricted only by the scope of the following claim.

What is claimed is:—

A pump of the character described comprising in combination, a housing having an open lower end, a pair of shafts rotatably mounted in the housing in spaced parallel relation to each other, gears carried by each shaft whereby to rotate one shaft reversely from the other, an outlet spout secured to the housing, a plurality of spaced interengaging spirally disposed liquid lifting blades mounted on said shafts, and cutter members carried by each of said shafts adjacent one end thereof and in spaced relation to the lowermost blade whereby to cut articles being drawn through the housing by the blades.

In testimony whereof I hereunto affix my signature.

JAMES D. FONVILLE, JR.
